BATHTUB ADAPTING MEANS

George Sakier, New York, N. Y., assignor to The Accessories Company, Inc., New York, N. Y., a corporation of Delaware

Application February 5, 1934, Serial No. 709,699

10 Claims. (Cl. 4—173)

My invention relates to improvements in bath room furnishings and the same has for its object the provision of simple, efficient and inexpensive means whereby bath rooms equipped with old forms of bath tubs may be readily and conveniently modernized.

Further, said invention has for its object to provide means whereby it becomes possible to remove an old style or form of bath tub supported on legs or feet, and replace the same with a bath tub of the "apron" type, without necessitating the tearing out of the old piping, and damaging the walls, floors, etc. of the bath room.

Further, said invention has for its object to provide an adapting member or element in the form of a relatively shallow panel or casing which may be readily interposed between the rear and side edges of the bath tub and the walls of the room adjacent thereto, and in which said panel or casing serves to receive and conceal the necessary piping.

Further, said invention has for its object to provide an adapting member or element for the purposes specified whose front wall portion serves to accommodate the necessary valves, spout, grab-bar, soap and sponge receptacles, and whose upper portion may serve as a shelf or support for bottles and other toilet articles or containers.

Other objects will in part be obvious and in part be hereinafter described.

To the attainment of the aforesaid objects and ends my invention consists in the novel features of construction, and in the combination, connection and arrangement of parts hereinafter more fully described and then pointed out in the claims.

In the accompanying drawing—

Figure 1 is a front elevation showing a bath room and corner tub, and one form of adapting means constructed according to and embodying my said invention in connection therewith;

Fig. 2 is an enlarged detail front view, partly broken away and in section, showing the means of securing the upper portion of the adapting means to the wall;

Fig. 3 is an enlarged detail sectional view on the line 3—3 of Fig. 1, and

Fig. 4 is a view similar to Fig. 3 illustrating a modification.

In said drawing 10 designates a corner bath tub of the well-known "apron" type comprising a receptacle portion 11, and front and end apron walls or portions 12, 13, respectively. The tub 55 is provided along its rear upper edge, and along

its right-hand vertical edge with an enlarged, or thickened rearwardly-extending rim portion 14.

15 denotes an adapting member in the form of a hollow panel or casing including a transverse top 16 and a side 16^a, from whose forward edges extends a vertical front wall portion 17, and from whose rear edge extend downwardly and inwardly, short longitudinal and vertical flange portions 18, 18^a, respectively. The said adapting member 15 is preferably formed of sheet metal and enameled, coated or otherwise decorated, as desired, and is secured in position with respect to the bath tub and the adjacent wall by means hereinafter described.

19, 19^a denote relatively narrow, longitudinal strips or plates of metal or other suitable material provided along their upper and outer edges with offset portions 20. The said strips or plates 19, 19^a are rigidly secured to the wall 21 by screws or other securing means 22. The offset portions 20

20 are adapted to receive and retain the flanges 18 of the transverse portions 16, 16^a of the casing. The inner edges of said front wall portion 17 terminates in front of the enlarged rim portion 14 of the tub 10 a short distance from the horizontal and vertical surfaces of the tub flanges. The outer surface of said wall portion 17, along its inner edge, is confined and maintained in position by a molding strip or finishing member 23, which is here shown as of quadrant shape in cross section with its underside or base resting upon the outer surface of the tub flange 14, and its inner or vertical side engaging the outer side of the front wall member 17. The molding strip or finishing member 23 is preferably made of pliable metal, such as white metal or any suitable alloy which is pliable to permit of its being shaped or conformed to the contour of the bath tub, and may be secured to the top and sides of the tub by cementing, or by any convenient mechanical means such as screws 24. The rear or inner surface of said molding strip or finishing member 23

25 contacts with the outer surface of the wall portion 17, while the space between the rear of the said wall member 17 and the forward portion of the rim 14 may be filled with cement 25 to insure a more perfect joint. It is preferable, however, to have a space between the inner edge of the front wall 17 and the adjacent surface of the tub 30 so as to prevent the edge of the front wall 17 becoming freed from the molding strip 23 should the tub 10, or the floor sink somewhat due to settling.

35 The space within the adapting member 15 is designated to receive the hot and cold water 40

45

55

supply pipes 26, 27, as well as other necessary pipes forming part of the plumbing system, and the front wall portion 17 is also suitably apertured to permit of the connecting and attaching 5 of the spout 28, and valves 29 controlling the supply of water thereto. The front may also be suitably recessed to provide soap and sponge receptacles 30, 31, respectively.

In the modification illustrated at Fig. 4 the 10 construction of the adapter 17 is the same as hereinabove described, and differs only in the form of the molding strip or finishing member 23^a, which may be formed either integrally with the tub or as a separate part and secured thereto 15 and is provided in its rearwardly-extended portion 23^b with a narrow longitudinal recess 23^c to receive and retain the inner edge of front wall portion 17.

While I have shown the panels or casings 15 20 as extending only a short distance above the top of the bath tub, it is to be understood that the same may extend upwardly to any height desired, even to the extent of covering the entire wall space between the top of the tub and the 25 ceiling of the room.

It is also to be noted that while I have shown the adapting members 15, and the connecting means therefor as applied to the back and one end of the tub only, it will, of course, be understood that the same may be applied at all of the 30 bounding edges of a tub, depending upon its construction, i. e., the number of ends of the tub which are to remain exposed.

Having thus described my invention what I 35 claim and desire to secure by Letters Patent is:

1. A bath tub adapter casing comprising a hollow member adapted to span the space between the edges of the tub and the adjacent wall portions of a room, and means for securing said 40 hollow member to said tub and said wall portions.

2. A bath tub adapter casing comprising a hollow member adapted to span the space between the edges of the tub and the adjacent wall portions of a room, said member including a trans- 45 verse portion and a vertical front portion extending therefrom, means for securing the rear edge of said transverse member to said wall portions, and the inner edge of said vertical front portion to the tub.

50 3. A bath tub adapter casing comprising a hollow member adapted to span the space between the edges of the tub and the adjacent wall portions of a room, said member including a trans- 55 verse portion and a vertical front portion extending therefrom, means for securing the rear edge of said transverse member to said wall portions, and a member secured to said tub adjacent to its rear edges for confining the inner edge of said vertical front portion to the edges of the tub.

60 4. A bath tub adapter casing comprising a hollow member adapted to span the space between the edges of the tub and the adjacent wall portions of a room, said member including a trans-

verse portion and a vertical front portion extending therefrom, means secured to the wall adjacent to the outer rear edge of said transverse portion and engaging said outer rear edge to secure said member to said wall portions, and a molding strip secured to said tub adjacent to its rear edge for confining the inner edges of said vertical front portion.

5 5. A bath tub adapter casing comprising a hollow member adapted to span the space between the edges of the tub and the adjacent wall portions of a room, said member including a trans- 10 verse portion, an inwardly-extending flange along the rear edge thereof, and a vertical front portion extending from the forward edge of said 15 transverse portion, a member secured to said wall portions having an offset edge to receive the inwardly-extending flange of said hollow member, and a molding strip secured to said tub adjacent to its rear edge in engagement with the 20 inner edges of said vertical front portion.

6. A bath tub adapter casing comprising a hollow member adapted to span the space between the edges of the tub and the adjacent wall portions of a room, said member including a trans- 25 verse portion and a vertical front portion extending therefrom, means for securing the rear edge of said transverse member to said wall portions, and a pliable molding strip secured to said 30 tub adjacent to its rear edges engaging and confining the inner edge of said vertical front portion.

7. A bath tub adapter casing comprising a hollow member adapted to span the space between the edges of the tub and the adjacent wall portions of a room, said member including a trans- 35 verse portion and a vertical front portion extending therefrom, means for securing the rear edge of said transverse member to said wall portions, and a molding strip secured to said tub 40 adjacent to its rear edges, said molding strip having a longitudinal recess therein receiving the inner edge of said vertical front portion.

8. A bath tub adapter comprising a member including a transverse portion and a vertical front portion, means for securing said member to the wall with the inner edge of said front portion overlying the contiguous edge of the tub, and a molding strip on the tub in engagement with said front portion at the inner edge thereof.

9. A bath tub adapter comprising a member secured to the wall with the inner edge thereof overlying the adjacent edge of the tub, and a molding member secured to the tub and confining said first named member at the inner edge thereof.

10. A bath tub adapter comprising a member secured to the wall with the inner edge thereof overlying the adjacent edge of the tub, and a pliable molding strip secured to the tub in engagement with said member at the inner edge thereof.

GEORGE SAKIER.
